SPARK PLUG

Filed Sept. 14, 1933

UNITED STATES PATENT OFFICE

2,047,031

SPARK PLUG

George M. Paulson, New York, N. Y., assignor to
 The B. G. Corporation, New York, N. Y., a corporation of New York

Application September 14, 1933, Serial No. 689,338

5 Claims. (Cl. 123—169)

This invention relates to spark-plugs and their ignition leads or conductors, and more especially to spark-plugs which are shielded against weather and oil and which together with their leads, are shielded against radio interference. The improvements constituting this invention are particularly applicable to aviation spark-plugs.

The insulated ignition leads usually lie more or less at right angles to the spark-plugs to which they are connected. The bending of the lead places a mechanical strain on the insulation, and this, combined with the heating from the engine, develops deterioration which frequently results in electrical break-down.

15 The objects of this invention are to provide a simple and advantageous means for protecting the ignition lead of a spark-plug both mechanically and against the effect of heat, also to provide weather-tight connections and electrical bonding connections between the metal harness of the lead and the spark-plug.

20 Spark-plugs have been provided with various forms of hoods or shields into which the lead has been brought laterally. In such devices the insulated lead is brought in straight, without bending the insulation, provision being made within the hood to establish electrical connection between the wire and the spindle of the plug.

Specifically, the present invention comprises 30 a combination of a particular type of radio-shielded spark-plug, a curved, tubular, metal elbow, which forms part of the complete spark-plug, and connections at the two ends of the elbow adapted to make weather-tight joints with the 35 spark-plug and with the lead and electrical bonds with the harness and with the grounded part of the plug. The spark-plug is one in which a metal barrel, united or connected with the grounded shell of the spark-plug, extends upward above the 40 spindle of the plug to provide a socket, which is lined with insulation. The insulated lead passes through the tubular metal elbow, which, therefore, requires no other internal insulation, and down into the socket of the spark-plug, where the 45 end of the lead is provided with a suitable terminal which automatically makes electrical contact with the spindle when the lead is inserted into the socket and the connection between the elbow and the spark-plug is made fast. One of the 50 connections grips or clasps the insulated lead so that it can not slip, and the connection between the elbow and the spark-plug constitutes a swivel which makes it possible to dispose the 55 elbow in any position.

In the accompanying drawing:

Fig. 1 is a longitudinal section illustrating an embodiment of the invention; and Fig. 2 is a view on a smaller scale, partly in section and partly in elevation, showing some of the elements of a 5 different form.

The details of the spark-plug may be varied. In the illustrated construction, the shell 2 is of conventional form, as is also the nut or bushing 3 screwed into the shell against a washer 4. A 10 spindle 5 surrounded by rolled mica insulation 6 and having a head 7 and an electrode 8, of conventional form, is gripped in the body of the plug so as to produce a gas-tight joint, in a known manner, by forcing a compressible metal ring 9 15 upward in a tapered opening of the nut. As is also customary, mica disc insulation 10 is confined between this ring and the head.

The metal body of the plug is provided with a barrel 11, which extends upward considerably 20 above the upper end of the spindle to enclose the spindle and the electrical connection between the same and the conductor which leads the high-tension current to the spindle. This barrel is preferably in one piece with the nut, though that 25 is not necessary in all cases.

The hollow interior of the barrel is of considerably larger diameter than the spindle and its insulating sleeve 6, and the barrel is lined throughout its length with a rolled mica sleeve 12, which 30 is inserted from the upper end of the barrel.

The space in the lower part of the barrel between the mica sleeves 6 and 12 is occupied by a stack 15 of mica washers, this stack bearing at its lower end against a metal washer 16, which in 35 turn bears on a shoulder 17 of the body. A thin cup 18 and a heavy metal washer 19 overlie the mica disc insulation, and the upper end of the spindle 5 passes through these parts and is upset at 20 to secure the cup in place and to confine 40 the mica disc insulation under more or less compression.

The insulated conductor or lead 13 is passed through a tubular, curved, metal elbow 21, which has a swiveled, detachable connection with the 45 barrel 11. A continuous braided metal sheath or harness 22 covers all of the cable up to the elbow, to which it is connected. The manner of securing the elbow to the insulated conductor and electrically connecting it to the metal sheath may 50 be varied. In the construction illustrated in Fig. 1, the outer end of the elbow has a screw-threaded enlargement 23, formed with a tapered mouth in which a conical rubber washer 24 is seated. A flanged collar 25 is soldered to the end of the 55

sheath 22 and bears against the washer 24, and a coupling nut 26 screws on the enlargement 23 to draw the collar against the washer and squeeze the latter against its tapered seat and inward to 5 clasp the insulation of the conductor.

The inner end of the elbow 21 is soldered or otherwise secured in the narrow upper end of a swivel coupling 27 designed for mechanical and electrical connection and disconnection with reference to the barrel 11. The lower part of this 10 detachable connection is large enough to pass over the barrel for a distance limited by an internal shoulder 28 abutting the end of the barrel.

The particular manner in which the elbow is 15 connected to the spark-plug may be varied. In Fig. 1, the lower part of the detachable connection is slotted longitudinally to form numerous resilient fingers 29 to clasp the barrel. The latter has an external circumferential shoulder or 20 recess 30 below its upper end, and the fingers have indent regions 31 to engage under this shoulder, the engaging surfaces being inclined, however, to permit the fingers to yield and the connection or 25 terminal 27 to be pulled off the barrel when a longitudinally slideable, rigid, locking ring 32 is forced upward.

The ring 32 has a circular internal groove 35 curved transversely to fit the humps 33. When the ring is forced downward so that the humps 30 seat in this groove, the indent portions 31 are positively locked with the shoulder 30, so that the connection can not be pulled off the barrel as long as the ring is in this position.

In Fig. 2, the construction of the spark-plug proper will be understood to be substantially similar to that described in connection with Fig. 1. Fig. 2 illustrates different forms of connections. It also shows that the lead may have a fabric covering 50 over the metal harness 32, in which 40 event the lead is prepared by cutting the covering 50 back a considerable distance from the end of the wire and cutting the metal shielding 22 back a somewhat shorter distance.

The outer end of the elbow 21a enters and is 45 firmly secured to a nipple 51, which is screw-threaded on the outside to receive a coupling nut 52, and the inside of which is formed with a tapering recess 53. The cut-back end of the metallic braiding 22 is turned back over a tapered 50 wedge ring 54, which is forced by the nut 52 into the tapered recess, thereby strongly gripping the metal braiding to the metal nipple, forming a tight joint and likewise holding the lead so that it can not pull out.

55 The connection between the inner end of the elbow and the barrel 11 comprises a thimble 27a fixed to the elbow and a coupling nut 27b, which screws onto the outside of the barrel and draws the member 27a against the end of the barrel, 60 forming a tight joint and a good electrical bond. Since the parts 27a and 27b can be turned in relation to each other, the connection may be said to be of a swivel nature; that is to say, the elbow can be disposed in any angular relation to the 65 spark-plug.

A length of the insulated conductor 13 projects below the connection member 27 or 27a to enter the socket of the barrel, lined by the mica sleeve 12. This portion of the conductor carries and 70 is surrounded by a tube of insulating material, for example a rolled mica tube 55, the opposite ends of which are bound by ferrules 36 and 37, similar to the ferrule which binds the upper end 75 of the lining sleeve 12.

This insulating tube acts as a spacer to prevent the conductor being pulled out of the spark-plug when the connection 27 is in place. The upper end of the tube, protected by the ferrule 36 bears against an internal shoulder 38 of said connection, whilst the ferrule 37 is connected with the stranded wire 39 of the conductor. 5

The ferrule 37 may be formed with an internal web 40 having a central opening. The strands of the conductor are passed through this opening 10 and bent outward, and a headed screw or pin fastening 41 is inserted upward through the hole into the body of the conductor, where it spreads and firmly engages the strands of the conductor wire, laterally compressing the insulation 42 of 15 the conductor.

The head of the fastening 41 also serves to secure to the end of the conductor the upper, small convolution of a conical contact spring 43, which latter makes a sure electrical connection with the 20 spindle 5 when the conductor is pushed into the barrel. The cup 42, or the washer 19, which may be regarded as part of the cup, forms a seat and an electrical contact for the base of this spring.

From the foregoing, it will be perceived that the 25 elbow is of a simple and inexpensive character, that electrical breakdown resulting from bending and overheating of the insulation of the conductor or lead is avoided, that the connection at one end of the elbow holds the lead and forms a weather- 30 tight joint, and also an electrical bond with the harness of the lead, that electrical connection between the conductor wire and the spindle of the spark-plug is made by inserting the projecting end of the lead into the socket of the spark-plug 35 and by securing to the plug the connection at this end of the elbow, and that this connection forms a weather-tight joint and an electrical bond with the grounded part of the spark-plug, and also affords a swivel. In a shielded spark-plug of the 40 general character illustrated, the insulation of the portion of the lead inside the barrel or socket of the spark-plug is particularly subject to heating, because of the heat flowing through the metal of the spark-plug from the inner end of the plug, 45 which is exposed to the high temperatures in the engine. In this invention, the elbow has a metal to metal connection with the barrel 11, and provides additional cooling surface on the metal of the plug. It results from this that the spark-plug 50 is kept at a lower temperature than it would be without the elbow, and this aids materially in saving the insulation of the lead inside the barrel of the plug from breakdown due to heat. Thus, the elbow of the spark-plug serves several purposes. It protects the insulation of the lead from 55 too severe heating, as well as protecting this insulation from mechanical strain. It also forms part of the complete electrical shielding of the spark-plug and its lead, and it likewise forms part 60 of the weather shielding of the plug.

This application is a continuation in part of application Serial No. 479,684, filed September 4, 1930 (now Patent No. 1,930,322, dated Oct. 10, 1933). 65

I claim:

1. An elbow spark-plug, comprising a spark-plug having a body or grounded portion provided with a socket lined with insulation and extending above the spindle of the plug, a curved, 70 tubular, metal elbow through which the insulated ignition lead extends to enter said socket, a detachable connection between the inner end of said elbow and the top of the grounded portion of the spark-plug, and means gripping the lead at 75

the outer end of the elbow and forming a weather-tight entrance to the elbow.

2. An elbow spark-plug, comprising a spark-plug having a body or grounded portion provided with a socket lined with insulation and extending above the spindle of the plug, a curved, tubular, metal elbow through which the insulation ignition lead extends to enter said socket, a detachable connection between the inner end of said

10 elbow and the top of the grounded portion of the spark-plug, and a connection at the outer end of the elbow adapted to retain the insulated lead and to be electrically bonded to a metal harness.

3. The combination of a spark-plug having a 15 spindle and a body or grounded portion provided with a metal barrel which extends above the spindle to provide a socket, an insulated lead provided with a metal harness for radio shielding, a curved, tubular, metal elbow through which the lead with 20 its insulation is passed, the end of the insulated lead projecting below the elbow and being provided with a terminal adapted to make electrical connection with the spindle, a connection at the outer end of the elbow forming a weather-tight 25 joint with the lead and electrically bonded directly to the metal harness, and a connection at the lower end of the elbow adapted to make a detachable, swivel, weather-tight joint and an electrical bond with the barrel.

30 4. The combination of a spark-plug having an upwardly extending metal barrel lined with insulation and forming a socket to receive an insulated lead, a curved tubular metal elbow of sub-

stantial wall thickness providing a conduit for the lead immediately above the socket and adapted to be connected at its upper end with a metallic shielding of the insulated lead, and a metal to metal connection between the elbow and said barrel, said elbow providing additional cooling surface on the metal of the spark-plug and thereby protecting the insulation of the lead inside the spark-plug from breakdown due to heating. 5

5. A spark-plug construction comprising a 10 grounded body including a barrel portion having a socket lined with insulation and opening through the upper end of the barrel portion to receive an ignition lead, means in the socket for connecting the lead with the plug, threads on the 15 sides of the barrel portion adjacent its upper end, a metal elbow through which the ignition lead passes immediately above the barrel portion, a connection between the metal elbow and said barrel portion including an externally flanged end 20 member secured to the lower end of the metal elbow and resting on the upper end of the barrel portion, a coupling nut on the threads of the body portion, and a shoulder on said nut extending over the flange on the end member of the elbow 25 to fasten the elbow to the body of the plug, said nut and end member being of metal and serving as conductors of heat from the barrel portion to the elbow to increase the heat radiating surface of the spark plug, and means at the upper end of 30 said metal elbow for gripping the ignition lead to hold it against being pulled out of the plug.

GEORGE M. PAULSON.
